ELECTROMAGNETIC DEVICE.

1,076,481.

Specification of Letters Patent.

Patented Oct. 21, 1913.

Application filed May 29, 1912. Serial No. 700,511.

To all whom it may concern:

Be it known that I, STANLEY C. BRYANT, a citizen of the United States, and a resident of the city of Chicago, in the county of 5 Cook and State of Illinois, have invented a new and useful Electromagnetic Device, of which the following is a specification.

This invention relates to an electro-magnetic device, particularly to a device known 10 as a bell of the "locomotive type."

The primary object of this invention is to provide a means for minimizing the liability of the electro-magnetic device to become inoperative, by reason of an open circuit 15 at the reciprocating circuit controller, usually employed with such a device when used in the operation of bells.

Other objects and advantages will appear 20 as the description of the invention progresses, and the novel features of the invention will be particularly pointed out in the appended claims.

In describing the invention in detail, reference is had to the accompanying drawings, 25 wherein I have illustrated a preferred physical embodiment of my invention, and wherein like characters of reference designate corresponding parts throughout the several views, and in which—

30 Figure 1 is a front elevation of the form of bell and associated mechanism selected by applicant to illustrate his invention; Fig. 2, is a side elevation of the mechanism and bell shown by Fig. 1, with some parts broken 35 away, and an electro-magnet coil and its connections removed; Fig. 3, is a schematic view showing a circuit arrangement for controlling the mechanism shown by Figs. 1 and 2.

40 1 designates a gong, of the locomotive bell type, fastened by means of the bolt 2 to the upper end of a curved standard 3, which is fastened at its two ends, by means of bolts 4, to a supporting base 5. The 45 curved standard 3 supports, at its upper end, the pin 6, which is rigidly attached to the standard at either end as best shown in Fig. 1, so that it cannot rotate. Upon the pin 6 a two arm lever 7 is pivoted, having at one 50 end the hammer 8, and being connected at the other end, by means of a pin 9, with a member 10. The two arm lever 7 is prevented from moving longitudinally of

pin 6, by being placed between two collars 11, both of which are fastened rigidly by 55 means of pins 12 to the pin 6. A rod 13 passes through a hole in the lower end of member 10 and bears a collar 14 at its upper end, so that the rod 13 cannot become detached from the member 10, thus 60 forming a slideable connection with the member 10. The rod 13 is attached by means of pin 15 to the cross bar 16, and is long enough to be inserted in a hole 17 in the base 5, which will serve to guide the 65 rod 13. The rod bears the adjustable collars 18, 19 and 20; the collar 18 being adapted to engage with the end 21 of a two arm lever 22, which is pivoted on pin 23; the collars 19 and 20 being adapted to engage 70 with the arm 24 of the three armed crank 25, which is pivoted on pin 26. The pin 26 is supported by standards 36 and 37.

The cores 27 and 28, connected by cross bar 16, are both V shaped at their inner ends 75 as best shown at 29 in Fig. 1, and are caused to move downwardly by reason of the magnetic attraction of cores 30, also best shown in Fig. 1. The cores 30 have brass pins 31 inserted therein to prevent cores 28 and 30 from 80 actually coming into contact one with the other and, consequently, being held together by residual magnetism. The cores 27, 28 and 30 are surrounded by coils of insulated wire 32 and 33, which, when a current of 85 electricity flows therethrough, cause a magnetic flux to flow in the cores and through the magnetic yoke 34, which is attached to the bottom of the cores 30 by means of screws 35. When a magnetic flux flows in 90 the path above described, the cores 27 and 28 are drawn downwardly.

Two standards, 36 and 37, are attached to the base 5 by means of screws 38 and are attached, one to the other, by means of 95 cross piece 39, which is attached to each at the end of an outstanding arm 40, by means of rivet 41. An outstanding arm 42, on each of the standards, forms a support for pivot pin 23. Screws 43 pass through the 100 upper ends of the standards 36 and 37 and into the ends of a magnetic core having the pole pieces 44. The core, having the pole pieces 44, supports the coil of insulated wire 45. The two armed lever 22 supports an 105 armature 46, which, when in the position

as shown in Fig. 2, is out of range of the magnetic attraction of the pole pieces 44. The two armed lever 22 also has attached thereto, by means of rivet 47, the bridging contact 48, which, when in the position as shown in Figs. 1 and 2, rests upon two standards 49 and 50 and makes metallic connection therebetween.

Standards 49 and 50 rest upon the base 10 5 and are attached thereto, by means of the bolts 51 and 52, which serve as binding posts for wires and which also serve to clamp the springs 53 and 54 in place. The standards 15 49 and 50 bear screws 55 and 56 for adjusting the position of springs 53 and 54.

The T crank 25 has an upper arm 57, which has the grooved upper surface 58 and 59 in which a roller 60, borne by a spring arm 61, which is supported by cross piece 39, is adapted to bear. The spring arm 20 61, acting through the roller 60, causes the T crank 25 to assume either one of two positions; with the roller bearing on the lowest part of the grooved surface 58 or the roller bearing on the lowest part of the grooved 25 surface 59. The spring arm 61, acting through the roller 60, also acts as an over-center throwing device, that is, when T crank 25 has been moved from the position 30 shown in Fig. 2, to a position where roller 60 just passes the ridge 62, the spring arm 61, acting through the roller 60, causes the T crank to move quickly to the limit of its movement, so that the roller 60 can bear 35 upon the lowest portion of grooved surface 59. The T crank 25 bears a metallic conducting member 63, which, when in the position as shown in Figs. 1 and 2, makes electrical connection between springs 40 53 and 54, but when in the other position, which the T crank may assume, with the member 63 in the dotted line position as shown in Fig. 2, does not make electrical connection between springs 53 and 54.

Binding post 64 is connected, by means of wire 65, with one end of coil 33; the other end of coil 33 being connected by means of wire 66 with binding post 52. Binding post 51 is connected, by means of 50 wire 67, with one end of coil 32; the other end of coil 32 being connected with binding post 68, by means of wire 71. One end of coil 45 is connected with binding post 64, by means of wire 69; the other end of coil 55 45 is connected with binding post 68, by means of wire 70.

With all of the parts as shown in Figs. 1, 2 and 3; if a source of current were connected to binding posts 64 and 68, current 60 would flow in the following path: binding post 64, wire 65, coil 33, wire 66, binding post 52, spring 54, member 63, spring 53, binding post 51, wire 67, coil 32, wire 71, and binding post 68 to the other terminal of 65 the source. The current flowing in the above

traced path would cause cores 27 and 28 to be drawn downwardly, thereby, causing rod 13 to be drawn downwardly, which would cause hammer 8 to strike the gong 1, but just before the hammer 8 struck the gong 1, the collar 19, acting through the arm 24 of the T crank 25, and assisted by the spring arm 61, acting through the roller 60, would have caused member 63 to move from in contact with springs 53 and 54 to the dotted line 75 position as shown in Fig. 2, thus breaking the circuit heretofore traced, and consequently, allowing the hammer 8 by reason of its weight to fall back into the position as shown in Fig. 2. Just before the hammer 80 had reached its final position of rest, as shown in Fig. 2, the sleeve 20, acting through the arm 24 of the T crank 25, and assisted by spring arm 61, acting through the roller 60, would have caused the member 63 to again form an electrical connection 85 between springs 53 and 54, which, of course, would again cause the cores 27 and 28 to be drawn downwardly, so that just so long as the binding posts 64 and 68 were connected 90 with a source of electrical energy the gong 1 would be continually struck by the hammer 8.

The type of bell herein illustrated is particularly adapted, for what is known as 95 highway-crossing signals, which are used to notify pedestrians and others of the approach of a train to a highway crossing. When used for such purposes it may remain idle for a great length of time and being 100 exposed to the weather as it must needs be, although protected as carefully as possible, a strong wind is liable to shake the standard upon which the bell mechanism is placed, so violently, that the hammer 8 is caused to 105 oscillate and thereby cause the rod 13 and the arm 24 to be moved and it is very possible that the member 63 will be left in the dotted line position as shown in Fig. 2. In case member 63 were left in the dotted line 110 position as shown in Fig. 2, then a subsequent application of electric energy to the binding posts 64 and 68 would not cause current to flow to coils 32 and 33 in the path above traced, consequently, no sounding of gong 1 would take place.

The device herein illustrated being designed for use as a safety device upon railways must, in order to secure favorable attention, be so designed that any opportunity for a failure to operate must be entirely removed.

Applicant has provided a means for preventing a failure of the bell to operate under the conditions above outlined. Its mode 125 of operation is as follows: If member 63 remains in the dotted line position as shown in Fig. 2, then when electrical energy is connected to binding posts 64 and 68 the current may flow as follows: binding post 130

64, wire 65, coil 33, wire 66, binding post 52, standard 49, bridging member 48, standard 50, binding post 51, wire 67, coil 32, wire 71, and binding post 68 to the other terminal of the source. It will be seen that the path just above traced is independent of member 63 and it must also be realized, that if the path just above traced remains closed constantly, the hammer 8 would not fall back until the source of energy had been disconnected from binding posts 64 and 68. The path is not closed constantly, however, for upon the downward movement of rod 13, the sleeve 18 contacts with the end 21 of two armed lever 22 and raises bridging member 48 from in contact with standards 49 and 50, thus breaking the connection heretofore traced and by raising arm 46, brings it within the range of influence of coil 45, which thereupon holds the armature 46 and the bridging member 48 in the rest position until the source of energy is disconnected from binding posts 64 and 68 when the armature 46 and bridging member 48, by reason of gravity, fall to the position as shown in the figures. It will thus be seen that if by any chance the member 63 should be left in the dotted line position, as shown in Fig. 2, with the hammer 8 in the position as shown in Fig. 2, an application of energy to binding posts 64 and 68 would cause hammer 8 to be raised. In the ordinary type of locomotive highway crossing bell, if the member 63 gets out of step with the rod 13, the bell becomes inoperative, but in applicant's type of bell if the member 63 gets out of step with the rod 13, it is possible, as has heretofore been shown, to start the bell ringing. This is an extremely valuable feature, for many highway crossing bells are located in rural districts, far removed from the headquarters of the maintainer who has charge of such bells, so that if a bell becomes inoperative, for any reason, it will generally be several days before the maintainer can get to the bell and remedy the difficulty. A bell of applicant's type, however, is practically self maintained.

Although applicant has herein shown his invention as applied to a mechanism for causing a hammer to strike a gong, it is not to be understood that such is the only use which may be made of applicant's invention for by those skilled in the art it will be readily seen that the principle underlying applicant's invention is just as applicable to the mechanism for causing the flashing of a light as is now commonly done in highway crossing signals, or for both the flashing of a light and the ringing of a bell. The employment of the apparatus for such double purpose merely requiring the addition of a contacting means to coöperate with member 63 as is well understood.

Although applicant has shown his shunt

circuit from member 48 as being broken at two places, it is of course to be understood that it is not at all necessary to make two breaks in the shunt circuit, as those skilled in the electrical art well understand that one break is sufficient for the purpose. Although applicant has shown the circuit for the electro-magnets 32 and 33 as being broken at two springs 53 and 54, it is well understood by those skilled in the art that it is not at all necessary to have two breaks in the circuit as one will accomplish the same purpose.

Although applicant has particularly described the construction of one physical embodiment of his invention, and explained the operation and principle thereof; nevertheless, applicant desires to have it understood that the form selected is merely illustrative, but does not exhaust the possible physical embodiments of the idea of means underlying his invention.

What I claim as new and desire to secure by Letters Patent of the United States, is:

1. In an electro-magnetic device; a source of electricity, an electro-magnet in circuit with said source, a member operable by said electro-magnet in one direction and operable by gravity in the opposite direction, a circuit controller governed by said member in circuit with said electro-magnet and said source, a circuit shunting said circuit controller, means controlled by said member to open said shunt circuit, means to retain said shunt circuit open.

2. In an electro-magnetic device; a source of electricity, an electro-magnet in circuit with said source, a member operable by said electro-magnet in one direction and operable by gravity in the opposite direction, a circuit controller governed by said member in circuit with said electro-magnet and said source, a circuit shunting said circuit controller, another circuit controller in said last mentioned circuit, said member adapted to open said last mentioned circuit controller, and means energized from the source to retain said last mentioned circuit controller open.

3. In an electro-magnetic device: a source of electricity; an electro-magnet in circuit with said source; a member operable by said electro-magnet in one direction and operable by gravity in the opposite direction; a circuit controller governed by said member in circuit with said electro-magnet and said source; a circuit shunting said circuit controller; another circuit controller in said last mentioned circuit; a pivoted member bearing an armature by which said other circuit controller is controlled, said first mentioned member adapted to contact said pivoted member when operated by said electro-magnet and break said shunt circuit; a second electro-magnet energized from said source having a pole face which is normally too

far from said armature to move it, said armature being moved within the effective range of said pole face by the contact of said first mentioned member with said pivoted member, the pole face thereafter holding said armature in the moved position and the shunt circuit open; means to interrupt

the flow of current to both of the electro-magnets.

STANLEY C. BRYANT.
